(57) **CLAIM**

We claim the ornamental design for an envelope, as shown and described.

DESCRIPTION

FIG. 1 is a front plan view of an envelope showing the new design;

FIG. 2 is rear plan view thereof;

FIG. 3 is a right side elevation view thereof, the left side being a mirror image;

FIG. 4 is a top plan view thereof, the bottom plan view being a mirror image;

FIG. 5 is a cross-section view thereof taken along line 5-5 in FIG. 1; and

FIG. 6 is an enlarged view of portion of FIG. 5.

FIG. 7 is a front plan view of another embodiment of an envelope showing the new design;

FIG. 8 is rear plan view thereof;

FIG. 9 is a right side elevation view thereof, the left side being a mirror image;

FIG. 10 is a top plan view thereof, the bottom plan view being a mirror image;

FIG. 11 is a cross-section view thereof taken along line 11-11 in FIG. 7; and

FIG. 12 is an enlarged view of portion of FIG. 11.

FIG. 13 is a front plan view of yet another embodiment of an envelope showing the new design;

FIG. 14 is rear plan view thereof;

FIG. 15 is a right side elevation view thereof, the left side being a mirror image;

FIG. 16 is a top plan view thereof, the bottom plan view being a mirror image;

FIG. 17 is a cross-section view thereof taken along line 17-17 in FIG. 13;

FIG. 18 is an enlarged view of portion of FIG. 17;

FIG. 19 is a front plan view thereof, shown in an unassembled configuration; and

FIG. 20 is a rear plan view thereof, shown in an unassembled configuration.

(Continued)

FIG. 21 is a front plan view of yet another embodiment of an envelope showing the new design;
 FIG. 22 is rear plan view thereof;
 FIG. 23 is a right side elevation view thereof, the left side being a mirror image;
 FIG. 24 is a top plan view thereof, the bottom plan view being a mirror image;
 FIG. 25 is a cross-section view thereof taken along line 25-25 in FIG. 21;
 FIG. 26 is an enlarged view of portion of FIG. 25;
 FIG. 27 is a front plan view thereof, shown in an unassembled configuration; and,
 FIG. 28 is a rear plan view thereof, shown in an unassembled configuration.
 The dashed lines represent portions of the envelope that form no part of the claimed design.
